(57) **CLAIM**

The ornamental design for a combined fishing rod holder and caddy, as shown and described.

DESCRIPTION

FIG. 1 is a front elevational view of the combined fishing rod holder and caddy of the present invention;

FIG. 2 is a rear elevational view of the combined fishing rod holder and caddy of FIG. 1;

FIG. 3 is a right side elevational view of the combined fishing rod holder and caddy of FIG. 1, the left view being a mirror image thereof;

FIG. 4 is a top plan view of the combined fishing rod holder and caddy of FIG. 1;

FIG. 5 is a bottom plan view of the combined fishing rod holder and caddy of FIG. 1; and,

FIG. 6 is a top, front, right side perspective view in an alternate position (handle extended).

The broken lines showing of a fishing rod, tackle box and cooler in FIG. 6 are for illustrative purposes only and form no part of the claimed design.
